OF EVANSTON, ILLINOIS, ASSIGNEES TO VANDERCOOK & SONS, OF CHICAGO,
ILLINOIS, A CORPORATION OF ILLINOIS

PROOF PRESS

Application filed June 6, 1931. Serial No. 542,499.

Our invention relates to power driven printer's proof presses and the main object of the invention is to provide improved structure and arrangements for applying ink to the inking rollers.

Our invention is particularly applicable to the type of proof press in which inking rolls and the printing cylinder travel through an endless path and over the bed of the press, 10 the inking rollers inking the galley or set-up and the printing cylinder impressing the proof sheet to the set-up for the proof printing. Heretofore the ink supplying means for the inking rollers has usually been in the 15 form of a flat ink plate located on the machine for the travel thereover of the inking rollers and such arrangement has not been practical or efficient.

In accordance with our invention, the ink 20 supplying element is in the form of a cylindrical drum on which ink is distributed and in contact with which the inking rollers travel to receive a supply of ink.

Another feature of the invention is the 25 provision of simple and efficient means for applying and distributing ink on the ink drum.

Another feature of the invention resides in the provision for continuous preferably slow 30 rotation of the ink drum and controllable intermittent drive from the same driving source of the inking roll structure and the printing cylinder propulsion means.

The above enumerated and other features 35 of our invention are incorporated in the structure disclosed on the drawings, in which drawings

Figure 1 is a front elevation of a proof 40 press;

Figure 2 is a plan view of the press with parts thereof in horizontal section;

Figure 3 is a plan view of the supporting 45 base frame of the press showing the arrangement of the driving elements therein;

Figure 4 is a section on plane IV—IV of Figure 2.

The supporting base 1 for the press is in the form of a rectangular frame mounted on legs 2. The press body frame comprises the 50 front and rear walls 3 and 4, the end walls

5 and 6, and the top wall 7 forming the press bed. Bolts 8 extend transversely through the frame and are secured at their ends to bars 9 which at their lower ends are secured in brackets 10 extending from the base frame 55 1, the press body frame being thus supported above the base frame.

The side walls 3 and 4 of the press bed frame have at their upper edges the horizontal laterally outwardly extending rail 60 flanges 11 and 11', and at their lower edges have similar rail flanges 12 and 12', respectively, parallel with the upper flanges. At their left ends, the walls 3 and 4 have extensions 13 and 13' secured thereto whose outer ends are semi-circular, and adjacent to their peripheries these extension walls have grooves 14 and 14' therein, the outer wall 15 surrounding the channel 14 of the frame extension 13 forming a continuation of and connecting the rail flanges 11 and 12 of the side wall 3, while the outer wall 15' of the frame extension 13' forms a continuation of the rail flanges 11' and 12'.

Extending laterally from the opposite end 75 of the bed frame are posts 16 supporting the frame 17 and secured to the ends of this frame are the walls 18 and 18' forming continuations of the walls 3 and 4 of the press body and these walls have the channels 19 and 19', 80 respectively, similar to those in the walls 13 and 13' the outer wall sections 20—20' forming continuations of and connecting the rail flanges on the press body.

The walls 18—18' journal a cross shaft 21 85 whose axis is the center of the semi-circular ends of the channels 19—19' and outside of the walls 18—18' the shaft has secured thereto the front and rear chain sprockets 22—22', a drive sprocket wheel 23 being secured to 90 the rear end of the shaft outside of the sprocket 22'.

The extension walls 13—13' journal a shaft 24 and outside of the walls front and rear sprocket wheels 25 and 25' are held on the 95 shaft free to rotate thereon, these sprocket wheels being in alignment with the sprocket wheels 22 and 22' at the other end of the machine, a chain belt 26 receiving the front sprockets 22 and 25 and a chain belt 26' re- 100

ceiving the rear sprockets 22' and 25'. The frame 17 from which the sprockets 22-22' are supported is adjustable on the studs 16 by means of a screw 27 so that the chain belts 5 may be kept at the proper tension.

The chains 26-26' propel the inking roll carriage and the printing cylinder carriage. We have shown two inking roll carriages, each comprising end frames 28 connected by 10 parallel shafts 29 which support the inking roll structures, each of which has metallic end sections forming rollers 30 and the intermediate section 31 formed of suitable composition for receiving ink. The roller ends 15 30 engage against the outer faces of the rail flanges 11-12 and 11'-12' and the outer faces of the wall extensions 13, 18 and 13', 18'.

Each inking roll carriage end wall 28 supports rollers 32 for engaging the inner sides of the rail flanges and the outer sides of the channels in the walls 13-13' and 18-18', these channels being of a width substantially equal to the diameter of the rollers 32. By 25 means of brackets 33 extending from the end walls 28 of the inking roll carriage these carriages are connected with the chains 26 and 26' as clearly indicated on Figure 1. As the chains travel, the printing roll carriages are 30 propelled through an orbit defined by the rail flanges on the press body and the channels through the extension walls thereon. When the inking roller units travel along the upper part of the orbit the inking rolls 30 35 travel across the galley or set-up on the press bed 7 to apply ink to the galley or set-up.

The printing cylinder carriage comprises end walls 34 between which extends the shaft 35 which mounts the printing cylinder structure 40 comprising the metallic end sections 36 forming rollers and the intermediate section 37 of suitable material for printing purposes, the roller sections 36 engaging the outer faces of the rail sections forming the orbit of 45 travel. The walls 34 also support rollers 38 for engaging the inner sides of the rails and for traveling through the channels in the extension walls on the press body. Brackets 39 extending from the walls 34 connect with the 50 chains 26-26' and the connection with the chains is preferably spaced 180-degrees from the connection with the chains of the inking roll units. When the chains are propelled, the printing cylinder rolls across the galley or 55 set-up after a sheet has been applied thereto and the sheet is impressed against the galley and printed, the galley having been previously inked by the travel thereacross of the inking roll units.

60 Describing now our improved means for supplying ink to the inking rolls, a cylindrical ink drum 40 is secured to the shaft 24 between the extension walls 13-13' and the shaft at its rear end has the sprocket wheel 61, by which the shaft and the ink drum are

rotated. To the right of the ink drum a shaft 42 is journaled in the walls 13-13' and has secured to its rear end the drive sprocket 43. An inverted U-shaped frame 44 has sleeves 45 and 46 at the ends of its legs which receive the shaft 42 so that the frame 44 may reciprocate on the shaft. Between the upstanding arms 47 and 48 on the frame 44 is journaled the ink applying roll 49 on which ink is smeared to be applied to the ink drum 40. 70

On the front end of the shaft 42 is journaled on arm 50 having a sleeve 51 at its upper end for receiving and guiding a pin 52 extending rearwardly from the frame 44, the pin extending through a slot 53 formed in the adjacent wall 13, the slot being concentric with the shaft 42. Extending to the right from the base of the arm 50 is the lever 54 terminating in a grip 55, and by means of this lever the arm 50 may be swung so that, through the pin connection 52, the frame 42 may be swung toward the left to apply the ink supply roller 49 to the ink drum. 80

The yoke of the frame 44 supports a depending pin 56 journailling a cam roller 57 which engages in the camway 58 formed between the two cam members 59 and 60 secured on the shaft 42, the camway being of such direction that as the shaft 42 is rotated the frame 44 will be reciprocated on the shaft 42 longitudinally thereof to shift the ink supply roll 49 back and forth along the ink drum in order to uniformly distribute the ink thereon, so that when the inking rolls 30 travel through the track channels 14-14', which are concentric with the ink drum, the composition inking rolls 31 will roll along the face of the ink drum and receive a charge of ink for inking the galley or set-up on the press bed. To the right of the pin 52 the arm 50 supports a stud 61 from which a spring 62 extends downwardly and is anchored to the base frame 1. When the lever 54 is swung down to withdraw the ink supply roller 49 from the ink drum the spring action will be at the right of the rotation axis of the arm 50 and the spring will tend to hold the parts in this position. When the lever 54 is swung up to apply the ink supply roll to the drum, the spring action will be at the opposite side of the arm axis and the supply roll will be held yieldingly against the drum. 100

Describing now the driving elements, a motor 63 is mounted within the base frame 1 whose shaft, at its front end, supports a cone pulley 64 and a drive pinion 65. The pinion meshes with a gear 66 secured on the front end of a shaft 67 journaled on the frame 1 above the motor, and this shaft at its rear end supports the sprocket pinion 68 which is outside of the frame 1. A chain belt 69 is driven by the sprocket pinion 68 and this chain engages the drive sprocket 41 for the ink drum supporting shaft 24, and also the sprocket 110

43 for rotating the shaft 42. The chain also engages an idler sprocket 70 which is journaled on a stud 71 which is adjustable in a slot 72 in the rear wall of the frame 1 and by means of such adjustment the belt 69 will be kept at the proper tension. A belt 73 connects the cone pulley 64 with a cone pulley 74 which is loosely journaled on the front end of the shaft 75 journaled in the front and rear walls of the base frame 1. In front of the cone pulley 74 a clutch disc structure 76 is secured to the shaft 75 and behind the cone pulley a sleeve 77 is keyed to the shaft but is 10 slidable longitudinally thereon. At its front end the sleeve has secured thereto the clamp disc structure 78 so that when the sleeve is shifted forwardly the cone pulley 74 will be clamped between the clutch disc structure and the cone pulley will rotate the shaft.

20 At its rear end and outside of the frame 1 the shaft 75 supports the driving sprocket 79 for driving the chain belt 80 which engages the sprocket wheel 23 on the shaft 21 which supports the driving sprockets 22-22' for 25 the chains 26-26' hereinbefore described. An adjustable idler sprocket 81 on the frame 1 keeps the belt 80 in proper tension.

Near its rear end the sleeve 77 has the circumferential channel 82 for receiving the 30 rollers 83 on the end of the fork frame 84 which is secured to and extends upwardly from a shaft 85 journaled within the frame 1 at right angles to the shaft 75. Secured to the inner end of the shaft 85 is a treadle 35 lever 86 whose front end terminates in a foot plate 87 in front of the base 1, a spring 88 tending to hold the lever up with the fork frame 84 holding the sleeve 77 withdrawn to the rear so as to free the cone pulley 74 and 40 prevent rotation of the shaft 75. When the treadle lever is depressed the sleeve 77 is shifted forwardly and the cone pulley is clutched and the motor will then, through the belt 73, rotate the shaft 75 for travel of the 45 inking roll structures and the printing cylinder structure through their orbit. In the driving arrangement shown, the ink drum is driven at comparatively slow speed while the inking roll structures and the printing 50 roll structure travel at a greater speed, and the direction of rotation of the ink drum is opposite to that of the belts 26-26'. The inking rolls 31 thus travel over and around a considerable arc of the ink drum to receive 55 an ample and uniform coating of ink for delivery to the galley or set-up on the press bed. By means of the cone pulleys 64 and 74 the chains 26-26' may be given different speeds, three different speeds being available with the cone pulleys shown.

60 The motor and transmission elements driven thereby are enclosed within the frame 1 and may be accessible through a door 89 provided in the front wall of the frame. The 65 driving parts are thus protected and the op-

erator cannot come into contact therewith during operation of the machine. In order to enclose the driving parts on the press body and to protect the operator from contact therewith, sheet metal protecting walls 70 or covers 90 may be applied.

For supporting the work which is to be printed, a shelf 91 may be provided above the press bed. As shown, this shelf extends forwardly over the press bed from legs 92 75 which extend upwardly from and may be secured to the rear side of the press body by the cross bolts 8.

The circuit for the driving motor 63 is controlled by a switch structure 93 of any 80 suitable type. The switch is operable by a lever 94 extending from its switch element (not shown) and preferably provision is made to actuate the switch simultaneously with swing of the lever 54 to apply the ink supply roll to the ink drum. As shown, a link 95 connects the end of the switch lever 94 with an arm 96 extending from the hub of the arm 50. When the lever 54 is down and the ink supply roller is away from the ink drum, the motor switch is open. When the lever 54 is swung up to apply the ink supply 90 roll to the ink drum, the motor switch will be automatically closed and the motor starts and operates the machine. The spring 62 which 95 then yieldingly holds the ink supply roll to the ink drum will also yieldingly hold the switch in closed position.

Briefly describing the operation of the machine, when it is desired to operate the machine, the lever 54 is swung up to bring the ink supply roller 59 against the ink drum and to start the motor, a supply of ink having been previously applied to the roll 49. The operator then takes a sheet from the stock on the shelf 91 to be printed, and he lays the sheet on the galley or set-up on the press bed. He then depresses the treadle to shift the sleeve 77 for clutching the cone pulley 74 to the shaft 75 for propulsion of the 100 belts 26-26'. Usually, the sheet is laid on the galley after the inking rollers have traveled thereover for an application of ink thereto. If the inking roll structures are not in the proper position for such application of 105 ink to the galley before the machine is started, the operator depresses the treadle until the inking rolls are propelled to apply ink to the galley and a sheet to be printed is then laid on the galley ready for 110 travel thereover of the printing cylinder. The operator times his feeding so that a sheet will be applied to the galley or set-up immediately after travel of the inking 115 rollers over the galley so that the sheet will be in proper position for the printing cylinder. If the operator is not fast enough for continuous operation of the belts 26-26', he may stop the machine by releasing the 120 treadle after each time the printing rolls have 125

been carried across the galley or set-up, and then after a sheet has been properly positioned he can depress the treadle for propulsion of the belts 26—26' and travel of the printing cylinder over the sheet. The ink drum rotates continuously so that the ink thereon is kept at the proper consistency and to be received by the inking rolls for inking of the galley or set up. To entirely stop the machine, the lever 55 is swung downwardly, which operation withdraws the ink supply roll 49 from the ink drum and opens the motor circuit switch.

To quickly stop the chains 26—26' after release of the treadle, the brake disc 97 is provided on the rear end of the sleeve 77 for engaging the stationary brake disc 98 on the frame 1.

In the operation of the machine, it is of course necessary to prevent the printing cylinder 37 from engaging with the ink drum. We have provided a very simple and efficient arrangement for accomplishing this. It will be noted that the rollers 38 on the printing carriage are closer together than the rollers 32 on the inking carriage. With this arrangement, when the rollers 32 travel through the guideways 14 and 14', the inking rollers 31 are brought into intimate contact with the surface of the ink drum, but when the rollers 38 travel through the guideways, the printing cylinder will be held clear of the ink drum surface.

We thus provide a simple, practical and efficient power-operated proof press which assures adequate, clean and uniform application of ink to the inking rolls. We do not desire to be limited to the exact construction, arrangement and operation shown and described, as changes and modifications may be made without departing from the scope and principles of the invention as defined by the appended claims.

We claim as our invention:

45 1. In a printing press, the combination of a printing carriage supporting a printing cylinder, an inking carriage supporting inking rollers, a track for said carriages defining an orbit of travel therefor, a press bed parallel with a section of said track, a driving belt connected with said carriages, pulleys for said belt and supporting shafts therefor, said carriages being connected with said belt for successive travel over a setup on the press bed when the belt is driven, an ink drum concentric with one of said shafts with its cylindrical surface in the path of the inking rolls for travel thereover of said rolls and application of ink thereto, a driving source, a transmission train between said source and one of said shafts for driving of said belt, and a transmission train between said source and said ink drum.

50 2. In a printing press, the combination of a printing carriage supporting a printing cylinder, an inking carriage supporting inking rolls, a track for said carriages defining an orbit of travel therefor, a press bed parallel with a section of said track, a driving belt connected with said carriages, pulleys for said belt and supporting shafts therefor, said carriages being connected with said belt for successive travel over a setup on the press bed when the belt is driven, an ink drum concentric with one of said shafts with its cylindrical surface in the path of the inking rolls for travel thereover of said rolls and application of ink thereto, a driving source, a transmission train between said source and one of said shafts for driving of said belt, and a transmission train between said source and said ink drum.

55 3. In a printing press, the combination of the press bed, a printing cylinder, an inking roll, means for causing said inking roll and said printing cylinder to travel successively over said bed for application of ink to a setup on said bed and for printing from the inked setup, and an ink drum arranged for travel thereover of the inking roll to be supplied with ink.

40 4. In a printing press, the combination of the press bed, a printing cylinder, an inking roll, means for causing said inking roll and said printing cylinder to travel successively over said bed for application of ink to a setup on said bed and for printing from the inked setup, and an ink drum arranged for travel thereover of the inking roll to be supplied with ink, and means for rotating said ink drum independently of the printing cylinder and inking roll moving means.

45 5. In a printing press, the combination of the press bed, a printing cylinder, an inking roll, means for causing said inking roll and said printing cylinder to travel successively over said bed for application of ink to a setup on said bed and for printing the inked setup, an ink drum arranged for travel thereover of the inking roll to be supplied with ink, and means for rotating said ink drum in a direction opposite to that of the travel of said inking roll thereon.

50 6. In a printing press, the combination of the press bed, a printing cylinder, an inking roll, means for causing said inking roll and said printing cylinder to travel successively over said bed for application of ink to a setup on said bed and for printing from the inked setup, an ink drum arranged for travel thereover of the inking roll to be supplied with ink, and means for rotating said ink drum in a direction opposite to that of the travel of said inking roll thereover and at a slower speed.

55 7. In a printing press of the class described, the combination of a printing cylinder structure, an inking roll structure, a guide track for said structures, defining an orbit of travel therefor, means for propelling said structures for successive travel over the printing bed of the press, an ink drum concentric with a part of said track for pre-

senting its cylindrical surface for travel thereover by the inking rolls of the inking roll structure for applying ink thereto, and an ink supply roll adapted for engagement

5 with said ink drum for supplying ink thereto.

8. In a printing press of the class described, the combination of a printing carriage, an inking carriage, a guide track for said carriages defining an orbit of travel therefor,

10 means for propelling said carriages for successive travel over the printing bed of the press, an ink drum concentric with a part of said track for presenting its cylindrical surface for travel thereover by the inking rolls

15 of the inking carriage for applying ink thereto, an ink supply roll adapted for engagement with said ink drum for supplying ink thereto, means for rotating said ink drum, and means for axially reciprocating

20 said ink supply roll to cause uniform spreading of ink on said drum.

9. In a press of the class described, the combination of a printing cylinder structure, an inking roll structure, a track defining

25 an orbit of travel for said structures, means for moving said structures around said track for successive travel across the printing bed of the press, an ink drum concentric with a section of said track for en-

30 gagement by the inking rollers of the inking structure for application of ink thereto, an ink supply roll for said drum, a supporting frame for said ink supply roll supported to be axially shifted to reciprocate the ink sup-

35 ply roll when in engagement with the ink drum, means controlling the reciprocation of the ink supply roll supporting frame, and driving means for rotating said ink drum and for actuating said reciprocation control-

40 ling means.

10. In a press of the class described, the combination of a printing cylinder structure, an inking roll structure, a supporting track for said structures defining an orbit

45 of travel therefor, means for moving said structures around said orbit for successive travel thereof across the printing bed of said press, an ink drum concentric with part of said track for travel thereover of the inking

50 rolls of the inking structure to apply ink thereto, an ink supply roll for said ink drum and a supporting frame therefor, cam means for reciprocating said supporting frame for axial shift of said ink supply roll to uni-

55 formly spread the ink on said drum, and means for rotating said ink drum, and for actuating said cam means.

11. In a press of the class described, the combination of a printing cylinder structure,

60 an inking roll structure, a supporting track for said structures defining an orbit of travel therefor, means for moving said structures around said orbit for successive travel thereof across the printing bed of said press, an

65 ink drum concentric with part of said track

for travel thereover of the inking rolls of the inking structure to apply ink thereto, an ink supply roll for said ink drum and a supporting frame therefor, cam means for reciprocating said supporting frame for axial shift of said ink supply roll to uniformly spread the ink on said drum, and means for rotating said ink drum and actuating said cam means, said cylinder being rotated in a direction opposite to the direction of travel of said printing cylinder and inking roll structures.

12. In a press of the class described, the combination of a printing cylinder structure and an inking roll structure, a supporting track for said structures defining an orbit of travel therefor, means for propelling said structures for successive travel thereof over the printing bed of the press, an ink drum concentric with a part of said track

70 for travel thereover of the inking rolls of the inking structure for applying ink thereto, an ink supply roll for said drum, a supporting frame for said ink supply roll adapted to be

75 swung to move said supply roll into or out of engagement with said drum, reciprocating means for reciprocating said supporting frame for axial reciprocation of said ink supply roll to cause uniform spreading of ink on said drum, a driving source, and a driving transmission driven by said source and connected to rotate said ink drum and operate said reciprocating means.

13. In a press of the class described, the combination of a printing cylinder structure and an inking roll structure, a supporting track for said structures defining an orbit of travel therefor, means for propelling said structures for successive travel thereof over the printing bed of the press, an ink drum concentric with a part of said track for travel

80 thereover of the inking rolls of the inking structure for application of ink thereto, an ink supply roll and a supporting frame therefor adapted to be swung to move said supply

85 roll into or out of engagement with said drum, reciprocating means for reciprocating said supporting frame for axial reciprocation of said ink supply roll to cause uniform spreading of ink on said drum, a driving source, a

90 driving transmission driven by said source and connected to rotate said ink drum and operate said reciprocating means, and means controlled upon movement of said ink supply

95 roll against or away from said ink drum for rendering said driving source operative or inoperative.

14. An inking attachment for printing presses comprising an ink drum having its surface disposed for travel thereover of the press inking rolls, an ink supply roll for said ink drum and a supporting frame therefor adapted to be moved to carry said supply roller into or out of engagement with said drum, driving means for rotating said drum,

controlling means for said driving means, and means controlled by the movement of said ink supply roll into or out of engagement with drum for actuating said controlling means to render said driving means operative or inoperative.

15. An inking attachment for printing presses comprising a drum disposed with its circumference for travel thereover of the press inking rolls, an ink supply roll for said drum and a supporting frame therefor adapted to be moved to bring said supply roll into or out of engagement with said drum, an electric motor and a driving connection therefrom for rotating said drum, a switch for said motor, and a connection between said switch and said frame for closing said switch for operation of the motor when said frame is moved to apply said supply roll to said drum and to open said switch when said frame is moved to withdraw said supply roll from said drum.

16. An inking attachment for printing presses comprising a drum disposed with its cylindrical surface for travel thereover of the press inking rolls, an ink supply roll for said drum and a supporting frame therefor adapted to be moved to bring said roll into and out of engagement with said drum, said supporting frame being shiftable for axial shift of said supply roll when in engagement with said drum for equal distribution of ink on said drum, a rotary cam for shifting said frame, an electric motor and a driving train extending therefrom for operating said drum and said cam, a switch for said motor, and a connection between said switch and frame for causing closure of said switch when said frame is moved to apply said supply roll to said drum and for opening said switch when said frame is moved to withdraw said supply roll.

17. In a printing press of the class described, the combination of the press body, a printing carriage, an inking carriage, guide tracks on said body, guide rollers on said printing carriage and guide rollers on said inking carriage engaging said tracks and said tracks defining an orbit of travel for said carriages, means for propelling said carriages through said orbit, an ink drum concentric with part of said tracks for presenting its cylindrical surface for travel thereover by the inking rolls of the inking carriage for applying ink thereto, the guide rollers on said printing carriage being closer together than the guide rollers on said inking carriage whereby during travel of the printing carriage concentric with the ink drum the printing cylinder of the printing carriage will be held clear of the ink drum ink surface.

18. In a printing press, the combination of a press bed, a printing cylinder, an inking roll, means defining a closed orbit of travel for said cylinder and roll, means for moving said cylinder and roll through said orbit for

successive travel thereof over the press bed and a set-up thereon, an ink drum concentric with part of said orbit arranged for travel thereover of the inking roll to be supplied with ink, and means for holding said printing cylinder clear of said ink drum during travel thereof around said drum.

In testimony whereof, we have hereunto subscribed our names at Chicago, Cook County, Illinois.
